A CORPORATION OF ILLINOIS

INKING MECHANISM FOR ADDRESSING MACHINES

Application filed March 21, 1929. Serial No. 348,781.

This invention relates to inking mechanisms and more particularly to inking mechanisms for use in connection with addressing machines wherein the ink applying roller is supported on a reciprocable carriage for movement toward and from the stencil guideway.

The main objects of this invention are to provide an inking mechanism having an improved frame for supporting a transferring roller in position to transfer ink from a supply roller to the ink applying roller; to provide improved means for uniformly distributing ink over the surface of the transferring roller; to provide improved mechanism for reciprocating said distributing means; to provide an improved form and arrangement of yielding means for normally urging said transferring roller into contact with the supply and ink applying rollers and for detachably securing said frame to the reciprocable carriage; to provide improved mechanism for limiting the movement of said frame so as to separate said transferring and ink applying rollers when the ink applying roller approaches printing position; and to provide an inking mechanism of this kind wherein the transferring roller and its supporting frame may be readily removed as a unit from the reciprocable carriage.

An illustrative embodiment of this invention is shown in the accompanying drawings, wherein:—

Figure 1 is a front elevation of an improved inking mechanism with the impression roller shown in dotted outline.

Fig. 2 is a top plan of the same with portions thereof broken away.

Fig. 3 is a vertical transverse section, taken on the line 3—3 of Fig. 1 and showing the ink applying roller in its raised position in contact with the transferring roller.

Fig. 4 is a view similar to Fig. 3 but showing the ink applying roller out of contact with the transferring roller as it approaches printing position.

Fig. 5 is a perspective of the frame which supports the transferring roller.

Fig. 6 is a fragmentary transverse section

taken on the line 6—6 of Fig. 1, but omitting the carriage.

Fig. 7 is a fragmentary transverse section taken on the line 7—7 of Fig. 1, but omitting the reciprocable carriage and ink applying roller.

Fig. 8 is an enlarged section of the mechanism which reciprocates the distributing roller, the view being taken on the line 8—8 of Fig. 1.

An improved inking mechanism embodying this invention is adapted for use in many different types of machines but, in the specific form herein illustrated, the invention is applied to an addressing machine. Inasmuch as this invention relates particularly to the inking mechanism, parts of the machine not relating thereto and believed to be unnecessary to a complete understanding of the invention have been omitted from the drawings.

In the form shown, the improved inking mechanism includes an ink applying roller journaled in a reciprocable carriage and adapted to be rotated and inked by a transfer roller which receives ink from a supply roller. The transfer roller is carried by an improved form or frame which is detachably secured to the reciprocable carriage. A distributing roller is arranged in contact with the transfer roller and is continuously reciprocated by improved mechanism on the frame.

In order that the ink applying roller may cease rotating as it approaches printing position, improved mechanism is provided for stopping the frame above the lowermost position of the reciprocable carriage so as to disengage the ink applying roller from the rotating transfer roller.

In the embodiment illustrated, the inking mechanism is applied to an addressing machine comprising a pair of supports or brackets 1 mounted on a horizontal bed 2 having a pair of spaced rails 3 and 4 forming a guideway for supporting a series of stencils 5 which are fed step-by-step through the machine by means of an endless conveyer, not shown, so as to be operated upon by the printing mechanism and by various other mechanisms, not shown.

Journalized in the supporting brackets 1, is a shaft 6, which is adapted to be driven by suitable mechanism, not shown.

Mounted on the rail 3 is a guide 7 for guiding the endless conveyer, not shown, which feeds the stencils through the machine. A portion of the guide 7, as shown in Figs. 3 and 4, serves as a stop for limiting the downward movement of the transfer roller, as hereinafter described.

In the form shown, the improved printing and inking mechanism includes an ink applying roller 8 journalized in a reciprocable carriage 9, which supports a movable frame 10, on which is mounted a transfer roller 11 and distributing mechanism 12 for transferring a uniform coating of ink to the ink applying roller from a supply roller 13, which is fixed on the rotatable shaft 6.

The mechanism for rotating and inking the supply roller 13 is not a part of this invention and has been omitted from the drawings.

In the specific form shown, the carriage 9 comprises a pair of end members 14 and 15 connected to a cross brace 16 having an opening 17 for receiving the bolt of the mechanism, not shown, which oscillates the carriage for moving the ink applying roller toward and from the stencils. The carriage oscillating mechanism is shown and described in the co-pending application, Serial No. 348,782, filed March 21, 1929.

Formed on the end members 14 and 15, are bosses 18, which are journaled on bushings 19 on the shaft 6, which forms the pivot on which the carriage 9 oscillates.

The frame 10 is shorter than the carriage 9, so as to fit between the end members 14 and 15 of the carriage. In the form shown, the frame 10 comprises a top plate 20 integrally formed on a pair of end brackets 21, which are bifurcated at their outer ends, as shown at 22, so as to be adapted to fit over the shaft 6 at respectively opposite ends of the supply roller 13. The shaft 6 serves as a pivot on which the frame 10 oscillates.

Formed on the end brackets 21, are openings 23, in which is supported a fixed shaft 24, on which the transfer roller 11 is rotatably supported.

The ends of the shaft 24 project outwardly beyond the brackets 21 and are provided with flat bearing surfaces 25 for engagement with levers 26, which are arranged to normally urge the frame 10 into position for pressing the transfer roller 11 into firm contact with the supply roller 13 and ink applying roller 8.

The levers 26 are pivotally connected to the end brackets 14 and 15 of the carriage by pins 27. Formed on the lower ends of the levers 26, are shoulders 28, which engage the bearing surfaces 25 of the shaft 24. The upper ends of the levers 26 are connected to springs 29 anchored to the cross brace 16 of the carriage.

With this improved construction and arrangement of parts, the levers 26 yieldingly urge the roller 11 into effective contact with the rollers 8 and 13 and also detachably secure the frame 10 to the carriage 9.

In the embodiment shown, the improved distributing mechanisms 12 includes a roller 30 loosely mounted on a shaft 31, which is supported in elongated openings 32 formed in the brackets 21.

The shaft 31 is urged downwardly by means of springs 33, which yieldingly hold the roller 30 in effective contact with the transfer roller 11. The lower ends of the springs 33 extend through the shaft 31 and the upper ends thereof are secured to screws 34 secured to the top plate 20.

The distributing roller 30 is rotated by contact with the transfer roller 11 and is reciprocated axially relative to the roller 11 by means of a sleeve member 35 embracing a rotatable shaft 36, which is journalized in openings 37 formed in the brackets 21.

Formed on one end of the sleeve 35, is a bifurcated arm 38, which slidably engages an annular groove 39 formed in the distributing roller 30. Formed in the sleeve 35, is a radially disposed slot 40, in which is seated a pin 41. The outer end of the slot 40 is covered with a removable plate 42 having an aperture 43 through which the pin 41 may be lubricated.

The inner end of the pin 41 rides in a race 44, which is formed in the rotatable shaft 36. In the form shown, the race 44 comprises a pair of oppositely disposed spiral grooves communicating with each other so that, upon rotation of the shaft 36, the pin 41 travels from one spiral groove to the other and causes a reciprocation of the sleeve 35 and distributing roller 30.

The shaft 36 is geared to the transfer roller 11 by gears 45, 46 and 47. The gear 45 is fixed on the shaft 36 and the gear 46 is journalized on a stud 48 mounted on one of the end brackets 21 of the frame 10. The gear 47 is fixed on a hub 49 of the transfer roller 11.

In order to permit the ink applying roller 8 to cease rotating during the printing operation, it is necessary to disengage the rollers 8 and 11 before the ink applying roller engages the stencil.

The mechanism for disengaging the rollers 8 and 11 includes a pair of arms 50 mounted on the frame 10 in position to engage the stop 7 for limiting the downward movement of the frame 10 independently of the carriage 9.

In order to permit adjustment of the arms 50 relative to the stop 7, they are pivotally secured to the frame brackets 21 by pins 51. One end of each of the arms 50 has a shoulder 52 adapted to engage the stop 7. The other ends of the arms 50 are pivotally secured to links 53, which are adjustably secured to the top plate 20 of the frame by screws 54,

having knurled nuts 55 arranged to shift the links 53 longitudinally for securing the desired adjustment of the arms 50.

In operation, the stencils 5 are fed in a step-by-step movement along the guideway so as to position one stencil at a time directly below the ink applying roller 8. During the operation of the machine, the roller 13 is continuously rotated and the carriage 9 is oscillated by mechanisms not herein shown.

The transfer roller 11 is inked and rotated by the supply roller 13. During the rotation of the roller 11, the shaft 36 is rotated, thereby reciprocating the sleeve 35 and roller 30 through the action of the pin 41 and race 45. The reciprocating roller 30 distributes the ink uniformly over the surface of the transfer roller 11.

When the carriage 9 is in elevated position, as shown in Fig. 3, the ink applying roller 8 is inked and rotated by the transfer roller 11. On the downward stroke of the carriage 9, when the roller 8 approaches printing position, the shoulders 52 of the arms 50 engage the stop 7 for limiting the downward movement of the frame 10. As the carriage 9 continues its downward stroke, the ink applying roller moves out of engagement with the transfer roller 11 and is pressed downwardly upon the stencil. The roller 8 is resilient so that the portion thereof which engages the stencil is flattened by the pressure of the carriage 9 so as to apply ink to a considerable area on the stencil.

When it is desired to remove the transfer roller, the springs 29 are disengaged so as to permit the levers 26 to be moved out of engagement with the shaft 24. The entire frame 10, roller 11 and distributing mechanism 12 may then be removed as a unit from the carriage.

Although but one specific embodiment of this invention has been herein shown and described, it will be understood that numerous details of the construction shown may be altered or omitted without departing from the spirit of this invention as defined by the following claims.

We claim:

1. A device of the class described comprising a supporting member, an ink applying element on said supporting member, a frame detachably secured to said member, and an ink transferring roller mounted on said frame in position to engage said ink applying element, said frame and transferring roller being removable as a unit from said supporting member.

2. A device of the class described comprising a supporting member, an ink applying element on said supporting member, a frame detachably secured on said member, an ink transferring roller mounted on said frame in position to engage said ink applying element, and a distributing roller mounted on said

frame in engagement with said transferring roller, said frame and rollers being removable as a unit from said supporting member.

3. A device of the class described comprising a supporting member, an ink applying element on said supporting member, a frame detachably secured to said member, an ink transferring roller mounted on said frame in position to engage said element, means on said member for yieldingly urging said transferring roller toward said element, a distributing roller mounted on said frame in engagement with said transferring roller, and means on said frame for yieldingly urging said distributing roller toward said transferring roller, said frame and rollers being removable as a unit from said supporting member.

4. A device of the class described comprising a support, a supply roller on said support, a movable carriage on said support, an ink applying roller on said carriage, a frame detachably secured to said carriage, an ink transferring roller mounted on said frame in position to engage said supply and ink applying rollers, and a distributing roller mounted on said frame and engaging said transferring roller.

5. A device of the class described comprising a support, a shaft on said support, an ink supply roller on said shaft, a carriage pivoted on said shaft, an ink applying roller on said carriage, a frame pivotally and detachably secured to said shaft, a transferring roller on said frame, and means yieldingly urging said frame into position to press said transferring roller into contact with said supply and ink applying rollers.

6. A device of the class described comprising a reciprocable carriage, an ink applying element mounted on said carriage, a frame movably mounted on said carriage, an ink transferring roller mounted on said frame and adapted to engage said element, and a stop for limiting the movement of said frame to separate said roller and said element at a predetermined position in the stroke of said carriage.

7. A device of the class described comprising a reciprocable carriage, an ink applying element mounted on said carriage, a frame movably mounted on said carriage, an ink transferring roller mounted on said frame and adapted to engage said element, a shoulder on said frame, and a stop arranged to engage said shoulder at a predetermined position in the stroke of said carriage for limiting the movement of said frame so as to separate said roller and said element.

8. A device of the class described comprising a substantially horizontal bed, a support on said bed, a supply roller on said support, an oscillating carriage on said support, an ink applying roller mounted on said carriage so as to be movable toward and from said bed,

- a frame mounted on said carriage so as to be movable relative thereto, an ink transferring roller mounted on said frame for engagement with said supply and ink applying rollers, and a stop on said bed for limiting the downward movement of said frame to separate said transferring and ink applying rollers when said carriage reaches a predetermined position.
5. A device of the class described comprising a substantially horizontal bed, a support on said bed, a supply roller on said support, an oscillating carriage on said support, an ink applying roller mounted on said carriage so as to be movable toward and from said bed, a frame pivotally and detachably secured to said carriage, an ink transferring roller mounted on said frame for engagement with said supply and ink applying rollers, a stop on said bed, and an adjustable shoulder on said frame adapted to engage said stop for limiting the downward movement of said frame to separate said transferring and ink applying rollers at a predetermined position in the stroke of said carriage, said frame and transferring roller being removable as a unit from said carriage.
10. A device of the class described comprising a substantially horizontal bed, a support on said bed, a supply roller on said support, an oscillating carriage on said support, an ink applying roller mounted on said carriage so as to be movable toward and from said bed, a frame pivotally and detachably secured to said carriage, an ink transferring roller mounted on said frame for engagement with said supply and ink applying rollers, a stop on said bed, and an adjustable shoulder on said frame adapted to engage said stop for limiting the downward movement of said frame to separate said transferring and ink applying rollers at a predetermined position in the stroke of said carriage, said frame and transferring roller being removable as a unit from said carriage.
15. A device of the class described comprising a substantially horizontal bed, a support on said bed, a supply roller on said support, an oscillating carriage on said support, an ink applying roller mounted on said carriage so as to be movable toward and from said bed, a frame pivotally and detachably secured to said carriage, an ink transferring roller mounted on said frame for engagement with said supply and ink applying rollers, a stop on said bed, and an adjustable shoulder on said frame adapted to engage said stop for limiting the downward movement of said frame to separate said transferring and ink applying rollers at a predetermined position in the stroke of said carriage, said frame and transferring roller being removable as a unit from said carriage.
20. A device of the class described comprising a substantially horizontal bed, a support on said bed, a supply roller on said support, an oscillating carriage on said support, an ink applying roller mounted on said carriage so as to be movable toward and from said bed, a frame pivotally and detachably secured to said carriage, an ink transferring roller mounted on said frame for engagement with said supply and ink applying rollers, a stop on said bed, and an adjustable shoulder on said frame adapted to engage said stop for limiting the downward movement of said frame to separate said transferring and ink applying rollers at a predetermined position in the stroke of said carriage, said frame and transferring roller being removable as a unit from said carriage.
25. A device of the class described comprising a substantially horizontal bed, a support on said bed, a supply roller on said support, an oscillating carriage on said support, an ink applying roller mounted on said carriage so as to be movable toward and from said bed, a frame pivotally and detachably secured to said carriage, an ink transferring roller mounted on said frame for engagement with said supply and ink applying rollers, a stop on said bed, and an adjustable shoulder on said frame adapted to engage said stop for limiting the downward movement of said frame to separate said transferring and ink applying rollers at a predetermined position in the stroke of said carriage, said frame and transferring roller being removable as a unit from said carriage.

Signed at Chicago this 19th day of March, 1929.
